BOOKRACK

Anthony Raucci, Pittsburg, Calif., assignor to
The Interlocking Metal Displays Company,
Pittsburg, Calif.

Application April 30, 1940, Serial No. 332,515

4 Claims. (Cl. 211—42)

This invention relates to racks of the type commonly used in stores for the display of merchandise.

It is an object of the invention to provide a rack particularly adapted to the storage and display of magazines or other similarly shaped objects.

Another object of the invention is to provide a rack of the character described which is constructed of inexpensive light-gauge sheet metal and yet which is sufficiently sturdy to provide a rack possessed of a long useful life.

A further object of the invention is to provide a rack of the character described which is designed to be nested in union with an adjacent similar rack so that a unit self-supporting assembly of racks may be produced.

A still further object of the invention is to provide a rack of the character referred to which will support a quantity of magazines or the like in a neat compact group and which will preclude the possibility of the goods becoming disarranged or falling from the rack and becoming damaged.

The invention possesses other objects and features of advantage, which, together with the foregoing, will be specifically pointed out in the detailed description of the invention hereunto annexed. It is to be understood that the invention is not to be limited to the specific form thereof herein shown and described as various other embodiments thereof may be employed within the scope of the appended claims.

Referring to the drawing:

Figure 1 is a perspective view of the rack of my invention.

Figure 2 is a fragmental vertical sectional view of a portion of the side of the rack. The plane in which the view is taken is indicated by the line 2—2 of Figure 1.

Figure 3 is a transverse vertical sectional view of the lower portion of the rack. The plane in which the view is taken is indicated by the line 3—3 of Figure 1.

Figure 4 is a fragmental vertical sectional view showing the connector for securing a horizontally disposed pair of racks together.

In detail, the rack comprises a sheet metal bottom 4 having, along both side and rear edges, downturned flanges 6 and, along its front edge, an angularly inclined upwardly extending apron 7 provided at its extreme upper end with a retroserely bent flange 8 to form a protective bead 9 which lessens the danger of a person being scratched or cut by the otherwise unprotected

edge of the thin sheet metal. Lying contiguous with and rising parallel to the side flanges 6 is a pair of side plates 11 each being connected, as by spot welding 12, to the side flanges and each having, along its front inclined edge, a tab 13 which is attached, by spot welding 14, to the respective side edges of the apron 7 and whose upper end is tucked under the flange 8. Sheet metal angle bars, secured by spot welding 16 to the rear vertical edges of the respective side plates 11, form upwardly extending rear corner posts 17 and strips 18 of sheet metal, having their forward longitudinal edges rolled or folded to form protective beads 19 and secured by spot welding 21 to the upper edges of the respective side plates, form front corner posts which are slightly angularly inclined rearwardly of the rack so that the foremost upper corner of each front corner post is substantially vertically aligned with the forward end of the lower edge of the side plates 11. Tie bars 22, each formed of sheet metal and provided with protective rolled beads 23 along their longitudinal edges, are secured, by spot welding 24, in horizontal position to and medially of the ends of the respective front and rear corner posts. A continuous sheet metal strip 26, joined to the upper ends of the respective corner posts 17 and 18 by spot welding 27, extends along the two sides and across the back of the rack and has portions 28 thereof folded inwardly of the rack over the upper ends of the corner posts and extensions 29 of the end portions 28 bent upwardly to form a trough 31 bordering the sides and back of the rack. A pair of spaced, vertically extending back bars 32, which are each formed of sheet metal and provided with rolled or folded edges 33, are secured, by spot welding 34, respectively, to the bottom 4 and to the strip 26 which extends across the upper back of the rack. The back bars 32 are formed with a slight rearward slant.

As is shown by the dotted lines 36 of Figure 1, a group of magazines or the like may be placed in the rack with their lower edges resting on the bottom 4 and the back of the rearmost one of the group resting against the back bars 32. The rearward pitch given the group of books by the inclined back bars 32 is usually sufficient to maintain the books in an overbalanced condition tending to prevent their falling through the open front of the rack. However, in addition to this, I provide a retainer composed of relatively heavy wire bent to form a front bar 37 and integral side arms 38 which extend closely adjacent the inner surfaces of the sides of the rack toward

the rear of the latter and which are each provided with inwardly bent pivot portions 39 journaled in looped strips 41 of sheet metal suitably secured to and adjacent the upper end of each rear corner post 11. The retainer may, after a group of books has been positioned in the rack, be pivotally moved from its full line position shown in Figure 1 to its dotted line position so that the front bar 37 will overlie and engage the outermost book of the group and thereby insure that the books may not tumble from the rack and be damaged in falling to the floor.

It will be noted that the downwardly projecting flanges 6 of the bottom 4 have substantially the same spacing as the troughs 31 in the top rim of the rack. This permits two or more of the racks to be superposed in a stack, as shown in Figure 2, with the flanges 6 of one rack seated in the troughs 31 of the rack immediately below it thus forming a rigid self supporting structure. Where two or more vertical stacks of racks are to be secured together, to extend the number of racks laterally, a piece of thin sheet metal 42 bent to U-shaped form and straddling adjacent tie bars 22, as shown in Figure 4, or a piece of wire encircling the tie bars, will suffice to securely hold the adjacent stacks of racks against being separated.

The sloping apron 7 functions, when the fore-and-aft thickness of the group 36 of magazines or books is abnormal and several of the books rest on the inclined face of the apron, to convert the downward weight of the books resting on the incline to lateral pressure which tends to compress the group and still further decrease the liability of the books falling from the rack.

Having thus described my invention in detail, what I claim as new and desire to secure by Letters Patent is:

1. A rack of the character described comprising a sheet metal base, on which a stack of objects may be placed, having along its side and rear edges a downturned marginal flange and along its front edge an upturned angularly inclined apron, side plates secured to said marginal flanges of the sides of said base and each having thereon an end tab secured to said apron, corner posts secured to and rising from said side plates, a sheet metal member secured to the upper ends of the respective corner posts, and said sheet metal member having a portion thereof formed to provide a trough bordering the sides and rear of the rack, said trough being vertically aligned with the marginal flanges of said base.

2. A rack of the character described comprising a sheet metal base, on which a stack of objects may be placed, having along its side and rear edges a downturned marginal flange and along its front edge an upturned angularly inclined apron, side plates secured to said mar-

ginal flanges of the sides of said base and each having thereon an end tab secured to said apron, corner posts secured to and rising from said side plates, a sheet metal member secured to the upper ends of the respective corner posts, said sheet metal member having a portion thereof formed to provide a trough bordering the sides and rear of the rack, said trough being substantially vertically aligned with the marginal flanges of said base, and an element pivotally mounted on said rack and movable to a position engaging the stack of objects on said base.

3. A rack of the character described comprising a sheet metal base, on which a stack of objects may be placed, having along its side and rear edges a downturned marginal flange and along its front edge an upturned angularly inclined apron, side plates secured to said marginal flanges of the sides of said base and each having thereon an end tab secured to said apron, corner posts secured to and rising from said side plates, a sheet metal member secured to the upper ends of the respective corner posts, said sheet metal member having a portion thereof formed to provide a trough bordering the sides and rear of the rack, said trough being substantially vertically aligned with the marginal flanges of said base, inclined back bars, against which said stack of objects may rest, secured at their respective ends to said sheet metal member and to said base, and an element pivotally mounted on said rack and movable to a position engaging the stack of objects on said base.

4. A rack of the character described comprising a sheet metal base, on which a stack of objects may be placed, having along its side and rear edges a downturned marginal flange and along its front edge an upturned angularly inclined apron, side plates secured to said marginal flanges of the sides of said base and each having thereon an end tab secured to said apron, corner posts secured to and rising from said side plates, a sheet metal member secured to the upper ends of the respective corner posts, said sheet metal member having a portion thereof formed to provide a trough bordering the sides and rear of the rack, said trough being substantially vertically aligned with the marginal flanges of said base, inclined back bars, against which said stack of objects may rest, secured at their respective ends to said sheet metal member and to said base, and a retainer comprising a piece of relatively stiff wire formed to provide a bar, extending across the front of the rack, having integral side arms extending rearwardly of the rack and pivotally mounted on said sheet metal member, and said bar being movable into a position engaging the said stack of objects on said base.
